UNITED STATES PATENT OFFICE.

ARTHUR PULLEN-BURRY, OF SOMPTING, WORTHING, ENGLAND.

MOVABLE HOTHOUSE.

1,076,230.

Specification of Letters Patent.

Patented Oct. 21, 1913.

Application filed June 30, 1913. Serial No. 776,666.

To all whom it may concern:

Be it known that I, ARTHUR PULLEN-BURRY, a subject of the King of Great Britain, residing at Rectory House, Sompting, Worthing, Sussex, England, have invented new and useful Improvements in Movable Hothouses, of which the following is a specification.

This invention comprises the application of shaft and gearing to hot houses of any length and any number of spans connected in such a manner that the whole of the building, pipes for hot water boilers, ventilating gear and water supply can be moved transversely, thus enabling one building to successively cover any number of like pieces of ground. These hot houses may be glazed or not as desired. This is effected by a framework of iron or timber upon which the roof, hot water pipes and cold supply are fixed, the framework moves transversely upon flat faced wheels over cement rails on a concrete bed at intervals of sixteen feet or more apart.

In order to keep the frame wheels on their pathway four or more horizontal wheels are fixed at the corners of the framework which press against the side of a steel rail mounted on a concrete bed. The ends of the hot houses ride upon this steel rail, and carry the first portion of the power producing gearing, the remainder of the power is produced by a long countershaft having pinions at intervals turning the driving wheels by a cog wheel attached to them.

The drawings illustrate a hot house made in accordance with this invention.

Figure 1 is a section and Fig. 2 is an end elevation, Fig. 3 is a plan and Figs. 4 to 6 show details to a larger scale.

The hot house shown consists of two spans mounted on wheels 10 and 11 at the ends and wheels 12 within the spans. The wheels 10 and 11 run on rails 13 and 14 respectively while the other wheels 12 run on concrete beds. At the ends also are horizontal wheels 101 and 111 which bear against the rails 13 and 14 and guide the path of the hot house.

On the center wheels 102, 112 and 122 of the wheels above mentioned are toothed wheels 103, 113 and 123, which are in gear with pinions 104, 114 and 124 on a shaft 15 extending the length of the house, one of the wheels 123 being shown in Fig. 4. The gear wheels 104, 114, 124, are cast in one piece

with sleeves 105, 115, 125, which are keyed to the shaft 15.

The shaft 15 is supported on the surfaces of the wheels 102, 112, 122, and is held in position by the sliding guide 16 which is in turn held by adjustable screws 17 moving through blocks 18 cast on the frame 19. By means of this adjustable guide any twisting of the shaft is allowed for.

The shaft 15 is turned by multiplying gear shown to a larger scale at Fig. 6. 20 is a handwheel keyed to a spindle 21 upon which is a pinion 22 in gear with another pinion 23 on the spindle 24. On the spindle 24 is a pinion 25 gearing with the toothed wheel 26 on the shaft 15 upon which are the pinions 104, 114, 124, as above described.

The hot house is provided all around its sides with hinged boards as are shown at 27.

The boiler 28 for heating the water to be circulated in the pipes 29 is provided with wheels to run on the rail 14. Or alternatively to run in a trench at one end of the hothouse upon wheels upon steel rails 281.

What I claim is:

1. A hot house, rails transverse to the hot house, wheels upon the hot house running on the rails, a longitudinal shaft carrying driving pinions, gearing connecting the driving pinions with the wheels, and means for driving the shaft.

2. A hot house, rails transverse to the hot house, wheels upon the hot house running on the rails, a longitudinal shaft carrying driving pinions, gearing connecting the driving pinions with the wheels, and multiplying gear for driving the shaft.

3. A hot house, rails transverse to the hot house, wheels upon the hot house running on the rails, a longitudinal shaft turning in adjustable bearings on the hot house and carrying driving pinions, gearing connecting the driving pinions with the wheels, and means for driving the shaft.

4. A hot house, rails transverse to the hot house, wheels upon the hot house running on the rails, a longitudinal shaft turning in adjustable bearings on the hot house and carrying driving pinions, gearing connecting the driving pinions with the wheels, and multiplying gear for driving the shaft.

5. A hot house, rails transverse to the hot house, wheels upon the hot house running on the rails, a longitudinal shaft carrying driving pinions gearing with toothed wheels on the wheels, and means for driving the shaft.

6. A hot house, rails transverse to the hot house, wheels upon the hot house running on the rails, a longitudinal shaft carrying driving pinions, gearing connecting the driving pinions with the wheels, means for driving the shaft, and other wheels at the ends of the hot house bearing against the sides of the rails.

7. A hot house, rails transverse to the hot house, wheels upon the hot house running on the rails, a longitudinal shaft turning in ad-

justable bearings and carrying driving pinions gearing with toothed wheels on the wheels, multiplying gear for driving the shaft, and other wheels at the ends of the 15 hot house bearing against the sides of the rails.

ARTHUR PULLEN-BURRY.
